Primary Examiner — Clare Ann Gannon

(74) Attorney, Agent, or Firm — Laurence A. Greenberg; Werner H. Stemmer; Ralph E. Locher

(57) **CLAIM**

The ornamental design for a decorative ribbon as shown and described.

DESCRIPTION

1. Decorative ribbon

1.2: Enlarged

1.5: Front

1.6: Left view; identical right view is omitted

1.7: Back

1.33: Front

The dashed lines represent articles of clothing to which the decorative ribbon is attached and forms no part of the claimed design. Color is not an element of the claimed design.

The design is a decorative ribbon with feather, buttons and glue, and the feathers in the applied state fall to various positions.

1 Claim, 5 Drawing Sheets
